(57) **CLAIM**

The ornamental design for a perforated carton, as shown and described.

DESCRIPTION

FIG. 1 is a perspective view of a perforated carton showing our new design;

FIG. 2 is a left side view thereof;

FIG. 3 is a right side view thereof;

FIG. 4 is a top view thereof;

FIG. 5 is a bottom view thereof;

FIG. 6 is a back view thereof;

FIG. 7 is a partial enlarged view of the left side top of the perforated carton as indicated by the broken line circle in FIG. 6;

FIG. 8 is a partial enlarged view of the left side bottom of the perforated carton as indicated by the broken line circle in FIG. 6;

FIG. 9 is a front view thereof;

FIG. 10 is a partial enlarged view of the right side top of the perforated carton as indicated by the broken line circle in FIG. 9; and,

FIG. 11 is a partial enlarged view of the right side bottom of the perforated carton as indicated by the broken line circle in FIG. 9.

In the drawings, the evenly spaced smaller broken lines are for the purpose of illustrating environment only and form no part of the claimed design. The larger evenly spaced broken lines are for the purpose of illustrating perforations that are part of the claimed design.
